UNITED STATES PATENT OFFICE

FRANZ ZACHARIAS, OF BROOKLYN, NEW YORK

SMOKING DEVICE

Application filed June 28, 1932. Serial No. 619,630.

The present invention relates to new and useful improvements in smoking devices and while it has been herein illustrated as embodied in a smoking pipe, it is capable of use in other devices such as cigar and cigarette smokers and the like.

It is the object of the invention to provide a new and improved type of coupling for attaching a bit or mouth piece to the smoking device proper.

A feature of the invention resides in a new and novel construction whereby liquids will be trapped and prevented from entering the bit or mouth piece.

Still a further feature of the invention resides in a novel construction whereby the bit may be readily attached and detached with respect to the smoking device.

The device of the invention lends itself particularly to the attachment of bits and mouth pieces to smoking devices in which the main body portion is formed from meer-schaum or similar material of more or less fragile nature.

Other features of the invention pertain to certain novel and improved constructions, arrangements and combinations of parts hereinafter described and particularly pointed out in the claims, the advantages of which will be readily understood and appreciated by those skilled in the art.

The invention will be clearly understood from the accompanying drawing illustrating the invention in its preferred form and the following detailed description of the constructions therein shown.

In the drawing,

Figure 1 is a view in elevation partly in section showing a smoking pipe, the bit of the pipe being attached to the body proper by a coupling constructed in accordance with the present invention.

Figure 2 is a plan view partly in section showing the bit disconnected with respect to the body of the smoking pipe.

Figure 3 is a detail sectional view taken on the line 3-3 of Figure 1, and;

Figure 4 is a distended view of the coupling per se.

Referring more specifically to the draw-

ing, 5 designates a pipe bowl, 6 the stem and 7 the bit. The stem has communication with the interior of the bowl by a passage 8 and the free end of the stem is provided with an enlarged socket or recess 9. The outer end of the socket or recess 9 is provided with an internal thread 10 and its outer extremity may be reamed to provide an angular wall 11.

The coupling comprises two members 12 and 13. The member 12 is a metal sleeve having a main body portion externally screw threaded as at 13' and a flared or bell extremity 14 which is adapted to seat in the reamed portion of the socket or recess 9, it being understood that the sleeve 12 is to be received in said socket or recess 9 and secured therein by means of the thread 13'. This thread 13' may be of such type as to form its own thread upon the interior of the socket or recess 9, or may be so formed as to fit a preformed thread in the socket or recess 9. The sleeve has a reduced portion 15 and a closed end 16, the latter being provided with an opening 17 to provide for communication between the socket or recess 9 and the interior of the sleeve 12.

The member 13 has a main body portion 18 which is centrally disposed and extending from one end thereof, there is a reduced body portion 19. These body portions 18 and 19 are formed with external threads 20 and 21 respectively. The member 13 is hollow and the thread 19 serves to secure it in the bit 7 as indicated by the reference character 22 in Figure 1. The member 13 is secured in the bit with its main body portion 18 projecting from the bit as best illustrated in Figure 2. The opposite end of the member 13 is reduced as at 23 and formed with a head 24. An opening 25 extends from the reduced portion 23 to the interior of the member 13 and the head 24 has a passage 25 extending therethrough as best illustrated in Figure 1.

These members will be of such proportions that when the bit is attached to the smoking device, the enlarged head 24 of the member 13 will engage the inner surface of the closed end of the sleeve 15 as illustrated at 30 in Figure 1. The passage 25 of the enlarged head 100

will register with the opening 17 in the closed end of the sleeve 15 and thus provide communication between the socket or recess 9 and the interior of the sleeve 15.

5 The device operates in the following manner.

Smoke passes through the passage 8 to the socket or recess 9 thence through the opening 17 of the sleeve 15 and through the passage 25 of the enlarged head 24 of the member 13 to the space 31 between the reduced portion 23 of the member 13 and the sleeve 15. From this point the smoke passes through the opening 25 into the hollow member 13

15 and to the bit 7.

Any moisture which may be carried in the smoke will be deposited either in the socket or recess 9 or the space 31 thus insuring the delivery of only dry smoke through the bit 7.

20 By reason of the fact that the sleeve 15 is made from relatively thin metal the same may be attached to a stem without necessitating the removal of any considerable amount of material from which the stem is formed 25 and this feature is of particular advantage where the stem or the smoking device is formed from meerschaum one characteristic of which is brittleness. As indicated by the reference character 30 the walls of the stem are of considerable thickness at the point where the sleeve is mounted thereby not detracting from the strength of the stem as is the case with the couplings of this pipe as ordinarily constructed.

30 The invention has been herein illustrated in its preferred form but it is to be understood that the invention is not to be limited to the particular construction herein shown and that it may be practiced in such other 40 forms as rightfully fall within the scope of the appended claim.

Having thus described the invention, what is claimed as new, and what it is desired to secure by Letters-Patent of the United 45 States, is:

A coupling for attaching bits to the stems of smoking devices said coupling comprising a sleeve having an internal and an external thread, said sleeve being receivable in 50 a socket in the stem and secured therein by said external thread, a flared outer end on said sleeve adapted to seat against the end of the stem and flush therewith, and a connecting member carried by the bit and projecting therefrom, said connecting member being provided with a thread for threaded engagement with the internal thread of the sleeve and an enlarged head on the free end of the coupling member, and adapted to engage the inner surface of the inner end of the sleeve when the bit and stem are in assembled position.

Signed at Brooklyn, New York, this 27th day of June, 1932.

65 FRANZ ZACHARIAS.
